UNITED STATES PATENT OFFICE.

SIMON SMITH, OF WEISBURG, INDIANA, ASSIGNOR OF ONE-HALF TO FRANK REHBERGER, OF MANCHESTER, INDIANA.

CHURN.

SPECIFICATION forming part of Letters Patent No. 637,425, dated November 21, 1899.

Application filed August 31, 1899. Serial No. 729,079. (No model.)

To all whom it may concern:

Be it known that I, SIMON SMITH, a citizen of the United States, residing at Weisburg, in the county of Dearborn and State of Indiana, 5 have invented a new and useful Churn, of which the following is a specification.

This invention relates to churns having a rotary vertical dasher, and has for its object to provide improvements in the manner of 10 mounting the operating means in conjunction with the dasher, whereby the latter may be removed without detaching the driving-gear or otherwise disturbing the latter. It is furthermore designed to provide an improved 15 hinge connection between the cover, which carries the dasher, and the operating means, whereby the cover may be conveniently opened and closed, and to permit of the use of the largest dasher possible without the latter binding upon the churn-body.

Another object is to provide an improved 20 churn-body having the parts thereof assembled in a simple and substantial manner, so as to prevent warping thereof and to provide 25 an exceedingly water-tight device.

To these ends the present invention consists in the combination and arrangement of parts, which will be hereinafter more fully described, shown in the accompanying drawings, and particularly pointed out in the 30 appended claim, it being understood that changes in the form, proportion, size, and minor details of construction may be made, within the scope of the appended claim, without departing from the spirit or sacrificing any 35 of the advantages of the invention.

In the drawings, Figure 1 is a perspective view of a churn constructed in accordance with the present invention. Fig. 2 is a longitudinal sectional view thereof, showing the 40 cover in open position. Fig. 3 is a horizontal transverse sectional view of the churn-body. Fig. 4 is a detail perspective view of one of the members of the hinge connection for the 45 cover.

Corresponding parts in the several figures of the drawings are designated by like characters of reference.

Referring to the accompanying drawings, 50 and particularly to Fig. 3 thereof, it will be seen that the churn-body is composed of sub-

stantially rectangular opposite side sections 1, a front 2, a rear or back section 3, and a bottom piece 4, the front, rear, and side sections being mortised together at the several 55 points of contact. The vertical edges 5 of the back section overlap or project laterally in opposite directions beyond the side sections, and two or more substantially U-shaped clamps 6 embrace the body of the churn and 60 have their opposite ends extending through the overlapping or laterally-projecting edges of the back section. Suitable metallic wear-plates 7 are fitted to the ends of the clamps and against the rear side of the back sec- 65 tion, and nuts 8 are provided upon the projecting threaded rear ends of the clamps, whereby the several sections of the body are conveniently and firmly connected together and an exceedingly water-tight body is pro- 70 vided. To prevent warping of the bottom piece, a metallic strap 9 extends across the under side thereof and has its opposite ends bent up against the opposite outer sides of the side sections, as at 11, and secured by 75 suitable fastenings.

The body is supported by means of opposite inverted and substantially V-shaped leg-standards 12, which are fastened to the opposite side sections of the body. It is preferable to employ opposite wear-plates 13, which are located at the outer side edges of the front piece 2 and let in flush with the outer face thereof, and also provided with notches 14 in their outer edges for the reception of the 80 respective clamps. Also it may be found convenient to provide the body with exterior grooves for the reception of the respective clamps, so that the latter may be flush with the outer faces thereof.

The upper open end of the body is closed by means of a substantially rectangular cover 15, which is provided at its opposite rear corners with hinge pintles or lugs 16, which project laterally at opposite sides of the cover. 95 Each of these pintles is adapted to engage a fixed hinge member 17, which is in the form of a flat plate-casting, having a longitudinal and slightly-arcuate slot 18, provided at opposite ends with rearwardly-extending branches 100 or notches 19 and 20. Extending downwardly at the front edge of the plate is an arm 21,

which is fastened to the side of the churn-body in advance of and against the front side of the adjacent projecting edge 5 of the back of the churn. Also the pendent arm 21 provides a transverse shoulder 22, which snugly fits the upper edge of the back of the churn, and thereby firmly mounts the hinge member in position. Upon the under side of the cover there is provided a rectangular block 23, which is located centrally and is adapted to fit the interior of the churn-body, and thereby prevent lateral movement of the cover during the operation of the churn. To lock the cover in the closed position thereof, there is provided a suitable spring-catch 24, comprising a flat strap of spring metal secured to the front edge of the cover and provided with an opening or perforation 25 for the reception of a pin 26, projecting laterally from the frontside of the churn-body.

The operating means comprises a drive-wheel 27, which is mounted upon an upright standard 28, carried by a yoke-shaped bracket 30, secured centrally to the top of the cover. Extending longitudinally and loosely through the standard 28 is a drive-shaft 31, carrying at its upper end a beveled pinion 32, which is in mesh with the drive-gear.

The dasher comprises a stem 33, having at its lower end the radial perforate blades 34 and provided at its upper end with a longitudinal socket 35, within which is received the lower end of the drive-shaft 31, and the latter is removably secured to the dasher-stem by means of a suitable pin or key 36.

It will be understood that the drive-shaft is capable of a longitudinal movement through the standard 28, so that by removing the pin or key 36 said shaft may be removed without interfering with the drive-gear 27. Furthermore, the dasher-stem is of larger diameter than the drive-shaft and is adapted to engage with the lower side of the arched bracket 30, which spans the opening 37 in the cover, and also the upper end of the dasher-stem, whereby the bracket forms a stop to limit the upward movement of the dasher and the drive-shaft and prevents the beveled pinion 32 from becoming disengaged from the drive-gear 27, as will be understood.

It will be noted that the dasher is nearly as large as the interior of the churn-body, and if the cover were connected by the usual hinge it would be impossible to open the cover,

as the dasher would engage the sides of the churn-body and prevent such opening. To obviate this difficulty, the present form of hinge has been provided. In opening the cover the spring-catch is disengaged, and the forward end of the cover is elevated sufficiently to raise the block 23 above the top edge of the churn-body. Then the cover is pulled forward until the pintles are alined with the respective longitudinal slots in the fixed hinge members, when the cover may be elevated until the pintles engage the upper ends of the slots and pass into the upper notches, after which the cover may be folded back upon the pintles as a center, the lower end of the dasher then being elevated sufficiently to clear the upper edge of the churn-body. In the closed position of the cover the hinge-pintles are located at the rear of the lower notches 20, and the upper walls of the latter engage the pintles, and thereby prevent accidental upward movement or displacement of the cover.

In order to facilitate the withdrawal of the buttermilk from the churn, as also the water when the churn is washed, an opening 40 is formed in one side of the churn-body adjacent the bottom and has a plug 41, although a spigot of any suitable form may be substituted for this plug.

Having thus described the invention, what is claimed, and desired to be secured by Letters Patent, is—

The combination with a churn-body and the cover thereof, of a hinge connection therefor, comprising opposite fixed hinge-pintles projecting laterally at opposite sides of the cover, and opposite members fitted to the churn-body, each member having a vertically-disposed slot receiving the adjacent pintle, and upper and lower, rearwardly-extending notches in communication with the respective upper and lower ends of the slot, the pintles being slideable in the respective vertical slots, and also adapted to be seated within the respective notches, substantially in the manner shown and described.

In testimony that I claim the foregoing as my own I have hereto affixed my signature in the presence of two witnesses.

SIMON SMITH.
